UNITED STATES PATENT OFFICE.

EARL T. AIKIN, OF LINTON, INDIANA, ASSIGNOR TO THE AIKIN DECORATIVE COMPANY, INC., OF LINTON, INDIANA, A CORPORATION OF INDIANA.

BURIAL-CASKET PLATE.

Application filed February 10, 1926. Serial No. 87,454.

The leading object of the present invention is to provide an article of the character stated comprised of a plate of elongated structure having removably attached with respect to its face an insignia bearing member.

A further object is to provide means whereby the same means which holds the insignia bearing member also holds a spray of flowers, ferns, or ribbons.

A further object is to provide a rear cover plate for concealing the insignia bearing member attachment means and the spray attaching means.

A still further object is to provide a space adjacent said spray of flowers upon which to delineate the name of the deceased, or such names as Mother, Father, Daughter, Son, At Rest, Rest in Peace.

Other and further objects will appear hereinafter.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in plan of a burial casket plate embodying the invention.

Fig. 2, is a fragmentary view in plan with parts broken away to show details of construction.

Fig. 3, is a view in section taken upon the line 3—3 of Fig. 1; and

Fig. 4, is a view in perspective of a removable insignia bearing member.

For the purpose of illustrating my invention I have shown in the accompanying drawings one form thereof which is at present preferred by me, since the same has been found in practice to give satisfactory and reliable results, although it is to be understood that the various instrumentalities of

which my invention consists can be variously arranged and organized and that my invention is not limited to the precise arrangement and organization of the instrumentalities as herein shown and described.

In the drawings the reference numeral 1 designates a plate of generally rectangular structure and of relatively thin metal having a marginal, flanged portion or rim 2

upon its rear face, the purpose of which will presently appear. At opposed corners are nail or equivalent penetrating securing medium holes designated 3, whereby the plate may be secured to a burial casket 60 either upon the outer or inner faces of the casket lid. Adjacent one of the holes 3, preferably the hole at the left hand lower corner of the plate, there are arranged a multiplicity of apertures or perforations 4 65 and 5, the apertures 4 being for the penetration of pins 6 as carried by an insignia bearing member 7; and the other apertures, or those designated 5, being arranged for the passage therethrough of the stems 8 of a 70 spray of artificial or other flowers 9. In this connection it is to be noted that the stems of the artificial flowers are caused to penetrate the apertures 5, and the pins 6 of the member 7 are thereafter bent in any 75 appropriate fashion to clamp the stems 8 of the spray of flowers 9 upon the rear side of plate 1. This not only firmly holds the insignia bearing member 7 in place but also firmly holds the spray in place. After the 80 spray of flowers has been secured to place there is preferably secured to the rear flange 2 of plate 1 a cardboard or like backing plate 10 as by glue or other suitable attachment means. Upon the face of plate 1 85 there is arranged a raised portion 11 suitable to receive the name of the deceased person contained in the casket to which the plate 1 is attached, and it is also desirable to delineate upon the member 7 the insignia 90 or other character designating the lodge, society, or the like of which the deceased person has been a member. Obviously the plate 1 may be finished in any desired style of metal, as nickel plate, bronze, copper, or 95 suitable tint, and obviously the spray of flowers 9 which are usually of artificial character may be finished to correspond with the fashion of the plate 1.

Having thus described my invention, what 100 I claim as new and desire to secure by Letters Patent, is:

1. As a new article of manufacture, a burial casket device comprising an elongated integral rectangular and flat plate 105 having a marginal rim at its rear, an insignia bearing member detachably secured adjacent one corner of said plate to the face of said plate, which member is provided with attachment means including a pair of 110

bendable prongs penetrating said plate, said plate being thin and flat a backing for said plate secured to said plate rear rim, and a spray of flowers the stems of which penetrate said plate and are secured with respect to the back of said plate by said prongs when bent.

2. As a new article of manufacture, a burial casket device comprising an elongated integral plate having a marginal rim at its rear, an insignia bearing member detachably secured to the face of said plate,

which member is provided with attachment means including a pair of bendable prongs penetrating said plate, a backing for said plate secured to said plate rear rim, means including an elongated raised portion upon the face of said plate to receive suitable insignia and a spray of flowers the stems of which penetrate said plate and are secured with respect to the back of said plate by said prongs when bent. 15 20

EARL T. AIKIN.
